UNITED STATES PATENT OFFICE.

FRANK BLANKENBERGER, OF PHILADELPHIA, PENNSYLVANIA.

MAIL CATCHING AND TRANSFERRING APPARATUS.

No. 928,735.

Specification of Letters Patent.

Patented July 20, 1909.

Application filed January 21, 1908. Serial No. 411,872.

To all whom it may concern:

Be it known that I, FRANK BLANKENBERGER, a citizen of Austria-Hungary, residing at Philadelphia, in the county of Philadelphia and State of Pennsylvania, have invented new and useful Improvements in Mail Catching and Transferring Apparatus, of which the following is a specification.

My invention relates to apparatus for supporting, catching, removing, suspending, transferring and delivering mail sacks carrying devices with respect to a moving train and has for its object the transfer of one or more sacks of mail matter in a simple and efficient manner without exposing the attendant during the time that the apparatus is in operation, so as not to endanger the life and limbs of such attendants when adjusting the mail for delivery and transfer.

Another object of my invention is the transfer of either one or more sacks in a single operation.

A further object of my invention is the transfer of the mail to a place where it can be safely removed.

A still further object of my invention is to allow the sacks to swing freely without being thrown against an object which might be damaged or cause the sacks to be damaged.

A further object of my invention is to prevent the mail-sacks carrying device from catching during its transfer.

A further object of my invention is to make my apparatus portable and reversible.

With these and other objects in view my invention consists in the combination and arrangement of parts as will be hereafter more fully described and claimed, and illustrated in the accompanying drawings, it being understood that changes in the form, proportion, size, and minor details may be made within the scope of the claims without departing from the spirit or sacrificing any of the advantages of my invention.

In the accompanying drawings Figure 1, is a perspective view of my improved apparatus in connection with a railway mail car; Fig. 2, is a plan view of my improved mail-sack carrier; Fig. 3, is a side view of the above, showing its position in the car doorway; Fig. 4, is a detail view of the car mail-sack carrier catching apparatus; Fig. 5, is a plan view of the same, also showing the manner of clamping it within the car; Fig. 6 is a perspective view of a doorway block;

Fig. 7 is a view of a swinging bracket in connection with the car mail catching apparatus; Fig. 8 is a view of a platform catching and delivering apparatus; and Fig. 9, is a detail view showing the manner of supporting the catching arm.

Similar figures refer to similar parts throughout the several views.

A mail car 2, having the usual door-opening 3, and floor 4, is provided on each side of the doorway with openings 5, 5', for inserting a removable and reversible mail sack carrier catching apparatus 6. Resting on the car floor 4, is shown a mail-sack carrier 7, on which mail sacks 8, are piled up and fastened thereto by ropes 9. In front of the mail car and at a fixed distance from the nearest rail 60, and preferably not less than 4 feet 4 inches therefrom is shown the platform apparatus 10, provided with a catching L 12', a platform 13, supported thereon a mail-sack carrier 7', said carrier being an exact counterpart of carrier 7, and consists of a plate 15, hooks 16, a ring 17 and projections 18.

The car mail-sack carrier catching apparatus 6, consists of a bracket 19, to be fastened within a car wall 60' as at 61, in front of the opening 5. The bracket 19, is channeled as at 20, for pivoting a double socket 21, on a pin 22, and for permitting said socket to swing as shown in the dotted position. The bracket 19, is provided with an inverted U 23, carrying a spring 24, to which 90 is attached a rod 25, formed into an axle 26, for a grooved wheel 27, to engage a rod 28, projecting from the socket 21. Two rods 29, 29' project from bracket 19, to support swinging catches 30, 30', provided with slots 95 31, 31' to pass over a pin 32 passing through the rod 28. Clamps 33, 33, support the bracket 19, in front of the opening 5.

The platform apparatus 10, consists of an upright 34, plates 35, 35, a platform 13, a brace 36, a catch 37, and a pocket 38. A bracket 39, is attached to upright 34, at 40, by bolts 41, 41. It carries a pin 42, on which is pivoted a socket 43, provided with a shoulder 44, to rest against bracket 39, at 63. 105 The socket 43, is thus held in a horizontal position when in use, but is free to be swung upward when not in use. From the double socket 21, projects an L 12, provided with a rod 45, on the leg 64, of the L, and with a 110 hook 46, on the arm 65. From socket 43 projects a similar L 12' provided with a rod

45' on the leg 64', and with a hook 46' on the arm 65'. The hook 46, is formed of a rod bent to slant from the end 47 of arm 65, as 48, then curved inwardly as at 66, then 5 straight and slanting but nearer to arm 65 than the projecting portion 46, as 49, then bent on itself as 50 and slanting toward arm 65. The hook 46' is in every respect similar to hook 46. The construction, form and 10 shape of these hooks are of prime importance and will be separately claimed. A block 53 is provided with pins 54, 54', to be inserted in holes 55, 55', of the car floor 4, to prevent the mail carrier 7, from being caught 15 within the car.

The *modus operandi* is as follows:—Assume a mail car moving in the direction of the arrow. The mail-sack carrier catching apparatus is clamped within the wall with 20 L 12 projecting through opening 5, and with its arm 65 pointing in the direction of the arrow. The slot 31 of bracket 30 is passed over the under portion of pin 32 to hold the L in a horizontal position. The mail 25 sack carrier is placed on floor 4, with projections 18 resting against the edge 58 of doorway 3, and with ring 17 projecting outward. The platform apparatus 10 posted in front of the track, preferably not less 30 than 4 feet 4 inches from the nearest rail, has its L 12' projecting toward the car with its arm 65' pointing in the opposite direction to the arm 65 of the L 12. On the platform 34 of upright 34, is placed a mail-sack 35 carrier 7' similar to that in the car doorway.

The L's 12, and 12' are in position to pass, as near as possible, through the centers of the rings 17, and 17'. As the car rushes by, hook 46 passes through ring 17', and sweeps 40 carrier 7' off platform 13. The ring 17 passes over hook 46 and impinges on the leg 64 of L 12, throwing it backward, which causes bracket 30 to drop, allowing spring 24 to cause rod 28 to swing until the arm 65 45 of L 12 projects within the doorway as shown by the dotted position. The momentum carries the carrier over the leg 64 of the L, until it strikes the rod 45 projecting therefrom, when its motion is reversed and is 50 caused to move on the inside of the hook due to its shape, until it strikes against the portion 46 of the hook where it is joined to the arm 65 of the L. It is then reversed again and forced between the slanting portions 49 55 and 50 of the hook where it remains suspended ready to be removed by the car attendant. The arm 65' of L 12' passes through ring 17 of carrier 7, and sweeps it out of the car doorway 3, block 53 preventing 60 it from catching in the doorway, and after passing through the same motions as carrier 7' remains suspended ready for removal. Should the mail car be running in an opposite direction, the car apparatus is 65 unclamped, and clamped in front of opening

5' in an inverted order, swing bracket 30' being substituted for bracket 30. Pin 67, is withdrawn from socket 43, L 12' turned half way around and the pin inserted again. When not in use, the car apparatus may be 70 removed, and the L 12' of the platform apparatus pushed up causing socket 43 to swing over pin 42 until the rod 45' passes within the pocket 38 of upright 34 and the top of the L passes under catch 37. 75

Having thus described my invention, what I claim as new and desire to protect by Letters Patent is:—

1. In combination with a railway mail car provided with doorways and a floor space, 80 openings on each side of the doorways, a bracket within the car and means for attaching the bracket in front of any one of the openings; a double socket pivoted in the bracket, a rod projecting from the socket 85 inwardly within the car, an L projecting from the socket outwardly, two rods projecting from the bracket within the car, swinging brackets provided with slots pivoted on said rods, a vertical pin passing through the 90 socket rod for the slot of either one of the swinging brackets to pass over it to hold the rod in a horizontal position, an inverted U attached to the detachable bracket, a spring mounted thereon, a rod attached to said 95 spring, having one end bent to form an axle, a grooved wheel mounted on the axle and engaging the socket rod to cause the socket rod to swing when the swinging bracket is off the pin. 100

2. The combination of a railway mail car and a channeled bracket mounted thereon, a double socket pivoted horizontally in the channel, a rod projecting inwardly from the socket an L consisting of a long leg and a 105 short arm at right angles to the leg projecting outwardly from the socket, a pin passing vertically through the inwardly projecting rod, a rod projecting inwardly from the detachable bracket, a bracket swingingly 110 mounted thereon and provided with a slot to engage the portion of the pin pointing downward to hold the socket rod in a horizontal position.

3. In combination with a railway mail car 115 provided with doorways and a floor space, an opening, and a detachable bracket attached within the car and in front of the opening, a double socket pivoted in the bracket, a rod projecting from the socket 120 inwardly, a pin passing through the rod and pointing upward and downward, a rod, a swinging socket pivoted thereon and provided with a slot to engage the pin on the underside of the socket rod to hold said rod in a 125 horizontal position, an L projecting from the socket outwardly, a hook attached thereto, an upright fixed in front of the car, a platform on top of said upright, a mail sacks carrier provided with a ring for the hook to 130

pass through it supported by the platform, to be swept off said platform by the projecting L as the mail car passes by the upright, said carrier to produce an impact on the L to cause it to move and release the swinging bracket to cause the spring on the inverted U to swing the L in front of the doorway.

4. In combination with a mail transferring apparatus mounted on a mail car provided with doorways and a floor space and moving on a track, a platform apparatus consisting of an upright fixed in front of the car track and not less than a fixed minimum distance therefrom, a bracket attached thereto, a pin carried by said bracket, a socket pin to swing over said pin, a movable L projecting from said socket, a pin to fix the L in said socket, a hook attached to the L, a mail sacks carrier provided with a ring and projecting through the car doorway for the hook of the L to pass through as the car runs past the upright to sweep said carrier out of the doorway, and a block attached to the car floor to prevent the carrier from catching in the doorway.

5. In combination with two mail catching apparatus mounted respectively on a mail car running on a track and on a platform in front of the track and provided with L's consisting of a leg and an arm, the end of said arm bent on itself and slanting away from the arm, curved inward and again slanting away from the arm, parallel to the first slanting portion, but nearer to the arm, then doubled on itself, and slanting inwardly toward the arm for the purpose set forth.

6. In a catching and transferring apparatus mounted on a mail car and comprising a double socket with a projecting rod and a projecting L, a bracket, a pin passing through the rod to be engaged by the bracket when an impact is produced on the L, and a device constituting the double means of first allowing the bracket to release the rod, and then causing the rod to swing.

7. In combination with a mail sack catching and transferring apparatus, a mail sack carrier consisting of a platform, hooks fastened therein and near the edges thereof, some of said hooks projecting through the platform, and a ring fastened to the platform midway between the projecting hooks for the purposes set forth.

8. In combination with a mail sack catching and transferring apparatus, an upright, a platform mounted thereon, to support a mail sack carrier and provided with an edge for the carrier projections to rest against it, a bracket attached to the upright, a pin and a socket pivoted thereon supported by said bracket, a movable L consisting of a leg and an arm, the leg supported in the socket, a pin to fix it in the socket, a hook attached to the arm, and a rod passing through the leg.

9. In a mail sack catching and transfer-

ring apparatus, an upright, a platform mounted thereon, a bracket attached thereto, a pin supported by the bracket, a socket pivoted on the pin, and a means in connection with the socket to hold the socket in a horizontal position.

10. In combination with mail sacks catching and transferring apparatus consisting of an upright fixed in front of a car track and provided with a socket and with an L having its leg extending from the socket and at right angles to the track and an arm parallel to the track, a railway mail car provided with a doorway and a floor space to support a mail sack carrier provided with extensions to be held in a fixed position of the doorway to cause a ring attached to the carrier to pass centrally over the arm of the L when the car is in motion.

11. In a railway mail car moving on a track the combination of mail sack catching and transferring apparatus consisting in a bracket, a double socket pivoted therein, a leg of an L extending from the socket exterior to the car and at right angles to the track, an arm at right angles to the leg, and a fixed upright in front of the track, a platform mounted thereon to support a mail sack carrier provided with extensions to rest against the platform in a fixed position and with a ring to allow the arm of the L to pass centrally through the carrier ring.

12. In a railway mail car provided with a doorway, a mail catching and transferring apparatus and comprising a pivoted double socket provided with an L consisting of a leg and an arm extending outward and a rod extending inward, a means to hold the socket in a horizontal position, said means to be released by an impact against the L, in combination with a means to cause the L to swing in front of the doorway and the arm of the L to pass within the doorway.

13. The combination of a railway mail car on a track and provided with doorways, a floor space and openings, and a fixed upright supporting a platform in front of the track, a mail sack catching and transferring apparatus consisting of a mail sack-carrier supported by the platform of the upright, a catching device swingingly mounted in a detachable and invertible bracket, a releasable means to hold the catching means in a horizontal position, a means to swing the catching device in front of the car doorway, a carrier on the floor and in the car doorway, a revoluble catching means swingingly supported by the upright, a means to hold said catching means in a horizontal position when the apparatus is in operation, and a means to hold the catching means in a vertical position when not in operation.

14. In combination with a railway mail car running on a track and provided with means for supporting a mail sack-carrier

and with means for catching a sack carrier, a fixed upright in front of the track and provided with means for supporting a sack carrier to be caught by the catching means provided by the car, and with a catching means to catch a mail sack carrier supported on the car at the time when the carrier on the upright is caught by the catching means provided by the car, and means attached to the

catching means to prevent the carrier from 10 slipping off the catching means.

In witness whereof I have hereunto set my hand and seal in the presence of two subscribing witnesses.
